(57) **CLAIM**

The ornamental design for a television receiver, as shown and described.

DESCRIPTION

1. Television receiver
1.1 is a front perspective view shown with display in fully retracted position.
1.2 is a front elevation view.
1.3 is a rear elevation view.
1.4 is a left side elevation view, the right side being a mirror image thereto.
1.5 is a top plan view.
1.6 is a bottom plan view.
1.7 is an alternate front perspective view shown with display in partially extended position.
1.8 is a front perspective view shown with display in fully extended position.
1.9 is a front elevation view.
1.10 is a rear elevation view.
1.11 is a left side elevation view, the right side being a mirror image thereto.
1.12 is a top plan view.
1.13 is a bottom plan view.
The broken lines depict portions of the television receiver that form no part of the claimed design.

1 Claim, 13 Drawing Sheets
